FEELER MECHANISM FOR LOOMS

Leonard E. Dunton, Franklin, Mass., assignor to Draper Corporation, Hopedale, Mass., a corporation of Maine

Filed Oct. 18, 1961, Ser. No. 145,885

4 Claims. (Cl. 139—281)

This invention relates to an improvement in a loom feeler mechanism and, more particularly, to that feeler mechanism employed for detecting the presence or absence of filling on bobbins in looms of the fly shuttle type.

It is a general object of the invention to provide a feeler mechanism with a more balanced and stabilized feeler action than has been used prior to the instant invention.

It is a further object of the invention to provide a feeler mechanism wherein the tension under which the feeler stem member is caused to function can be increased or decreased to the desired tension proper for a particular weaving condition.

It is a further object of the invention to provide a filling feeler with very little resistance to the movable components of the mechanism thereby increasing the life expectancy of said components.

It is a further and more specific object of the invention to provide a stabilized feeler mechanism in which the feeler member is centrally balanced and the lateral forces to which this member is subjected are counteracted through the combined stabilizing and tension action of springs extending obliquely from either side thereof.

Other objects of the invention will become apparent from the following more detailed disclosure.

In looms of the fly shuttle type wherein said shuttle supports a filling carrying bobbin, it is common practice to utilize a filling feeler mechanism to detect the presence of filling on the active bobbin and to initiate replenishment of this bobbin upon indication of exhaustion of the filling supply wound thereon.

An example of a filling feeler mechanism which utilizes the side slipping feature of the feeler element to actuate the means for bobbin replenishment similar to that of the instant invention is disclosed in United States Patent No. 2,556,136.

Filling feeler stems of the prior art having the side slipping feature are subjected to continued frictional contact with portions of the casings within which they are housed because of the spring means employed to continually urge the stem member to its fullest extended position and away from that position for indicating bobbin replenishment.

Continued reciprocation of the stem member within the feeler case during the presence of filling on the operating bobbin promotes wearing of this member and associated parts. Additionally, the stem member after side slipping to indicate bobbin replenishment snaps back to the guide members which position it in normal operating position creating an unstable condition which as a result of the force urging it to this position and its tendency to try to move beyond these points causes said stem member to rock to and fro against said guide members until said forces have dissipated.

Generally, the feeler according to this invention includes a feeler case, a slideable and pivotal stem member extending from said case and a feeler tip affixed to the end thereof, said stem member having a first portion extending in a direction substantially perpendicular to the axis of the bobbin from which it is adapted to derive an indication and a second portion extending from the forward end of said first portion and in a direction substantially perpendicular thereto, said feeler case including a

2

5 pivot member and a guide member generally aligned and centrally disposed for guiding the forward and rearward motion of said first portion of said stem member, the combination of said second portion and said pivot member being effective to limit rearward movement of said stem member and also being adapted to guide forward and rearward motion of said first portion of said stem member, a pair of oppositely disposed coil spring members for stabilizing and urging said stem member to a centralized and fully extended position from said feeler case, said springs having one end of each attached to adjacent points on said stem member, the latter having a plurality of such attaching points along the length of said first portion for selectively varying the spring tension imparted thereto, said spring members being disposed as to extend obliquely in the direction of the feeler tip from said first portion to opposed attachment points at the sides of said feeler case.

10 The mechanism of the instant invention provides a filling feeler unit of novel design which reduces to a considerable extent the undesirable wearing of the various components heretofore described by providing a centrally balanced and stabilized feeler stem member. This stem member as is well known to those conversant in the art is caused to reciprocate longitudinally during the period of detecting sufficient filling on the operating bobbin for continued weaving and to move in a lateral direction indicating filling exhaustion at which time it also initiates bobbin replenishment. The filling feeler case from which the stem member protrudes is provided with a pivot member and a guide member generally aligned and centrally disposed for guiding said stem member during movement thereof.

15 The means for urging the stem member to its fully extended position and for maintaining it in a balanced and generally centralized position within the feeler case comprises counteracting expansion springs attached at a common point to said stem member and extend obliquely from either side thereof to attachment points at the sides of said feeler case. The stem member being maintained in a balanced and generally centralized position has its outer portion, to which the feeler tip is affixed, offset from its shank portion to enable this member to side slip and initiate bobbin replenishment when making contact with a bobbin on which the filling yarn has become exhausted.

20 This means of spring control reduces the frictional contact that is normally had between the stem member and its guiding means as well as equalizing the lateral forces normally imparted to said stem while being urged to its fully extended position. Additionally, the stem member being centrally balanced in this manner eliminates the aforementioned tendency of an unstable feeler action when the stem member returns to its normal position from a transfer indicating position. To increase or decrease the amount of tension under which the stem member is caused to function, the counteracting expansion springs are adjustable longitudinally along the length of said stem member.

25 Further advantages of the invention will be evident from the following description and drawings, wherein:

FIG. 1 is a plan view of a filling feeler mechanism according to the invention showing the feeler tip and stem member in a fully extended position and by means of phantom lines adjacent thereto, the position assumed by said tip and stem member when detecting the presence of sufficient filling on the operating bobbin for continued weaving.

30 FIG. 2 is a view in side elevation of the filling feeler mechanism shown in FIG. 1.

35 FIG. 3 is a view similar to that of FIG. 1 but showing the position assumed by the feeler tip and stem

member when caused to move in a lateral direction on indication of filling exhaustion and to initiate replenishment thereof.

FIG. 4 is a sectional view taken along line 4—4 of FIG. 1.

FIG. 5 is a sectional view taken along line 5—5 of FIG. 1.

Referring to the FIGS. 1, 2 and 3 the feeler mechanism is indicated generally by numeral 10 which comprises a casing 11, casing cover 12 and a filling feeler which includes a feeler tip 13 and a stem member 14. The supporting stem indicated generally by numeral 14 protrudes from casing 11 through an opening 15 and has affixed to the offset free end protruding therefrom a feeler tip 13. That portion of stem 14 which assembles within the confines of casing 11 is centrally disposed and extends in a longitudinal direction from opening 15 to a pivot member 16 where at this point the stem is formed at substantially a right angle to the stem's shank portion 17 as at 18 and serves as a counterbalance for the offset portion of the stem which protrudes from the casing itself. Pivot member 16 along with one side of opening 15 as at 19 serves as a guide means to prevent the supporting stem 14 from moving in a lateral direction other than that of initiating bobbing replenishment.

The supporting stem 14 as shown in FIGS. 1 and 2 is continually urged to a centralized and fully extended position from casing 11 by means of counteracting expansion springs 20 and 21. These springs have one end thereof attached at a common point to the supporting stem 14 as at 22 and extending obliquely in the direction of feeler tip 13 from either side thereof their opposite ends are attached to pins 23 and 24 provided at the sides of casing 11.

When the filling yarn becomes depleted on the operating bobbin to the extent that replenishment is required, the feeler tip 13 when making contact with the bobbin (not shown) is caused to slip sideways as illustrated in FIG. 3 to the extent where the supporting stem 14 contacts and actuates a transmitter rod 25 which initiates a filling replenishment action well known to those familiar with the art.

The casing cover 12 is made of any suitable material and preferably one which is transparent such, for example, as one of the various types of plastics that are commercially available. It is assembled to casing 11 by means of a bolt 26 the shank portion of which passes through an aperture in the cover and thence through an aligned aperture in the casing. The threaded portion of bolt 26 extends through and beyond casing 11 and is adapted to secure the complete unit to a loom mounting bracket 27 a portion of which is shown in FIG. 5.

In addition to bolt 26, casing cover 12 is provided with a positioning means which comprises a pin 28 that protrudes from casing 11 and is adapted to be received by an aligned aperture provided in said cover.

In operation the stabilizing effect produced by the counteracting expansion springs tends to continually urge the supporting stem 14 to a centralized and fully extended position from the casing 11. To detect the presence or absence of filling on the operating bobbin, the feeler tip enters an opening provided in the loom shuttle on the forward movement of the lay when the shuttle is in a boxed position. If sufficient filling is present on the bobbin for continued weaving, the feeler tip and its supporting stem will move a short distance in a longitudinal direction and then through retraction of springs 20 and 21 it will move to its normal extended position as the lay commences to move in a rearward direction. When the filling yarn becomes depleted to the extent that replenishment is required, the feeler tip when making contact with the bobbin is caused to slip sideways to the extent where the supporting stem 14 contacts and actuates a transmitter rod 25 which initiates a filling replenishment action. As the lay commences to move in a rear-

ward direction the feeler tip and stem return to their regular and extended position through retraction of spring 20. The unstable condition normally created by the quick return of these members causing the stem member to rock to and fro against the guide members until the forces with which it was caused to return to this position had dissipated, are now controlled and equalized through the counteracting expansion springs. This novel feeler means provides a more stabilized feeler stem and balanced feeler unit with a minimum of frictional contact between the various components creating a favorable condition whereby the life expectancy of said components is increased to a considerable extent.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In a feeler mechanism for looms, the combination of a feeler case, a pivot member, a stem member having a first portion extending in a direction substantially perpendicular to the axis of the bobbin from which it is adapted to derive an indication and a second portion extending from the forward end of said first portion and in a direction substantially perpendicular thereto, said pivot member being effective to limit rearward movement of said stem member and also being adapted to guide forward and rearward motion of said first portion of said stem member, said stem member including a feeler tip affixed to the rearward end thereof, a pair of oppositely disposed resilient members for stabilizing said stem member in a centralized position within said case and said resilient members further urging said feeler tip and stem member to a fully extended position therefrom.

2. In a feeler mechanism for looms, the combination of a feeler case, a pivot member, a stem member having a first portion extending in a direction substantially perpendicular to the axis of the bobbin from which it is adapted to derive an indication and a second portion extending from the forward end of said first portion and in a direction substantially perpendicular thereto, said pivot member being effective to limit rearward movement of said stem member and also being adapted to guide forward and rearward motion of said first portion of said stem member, said stem member including a feeler tip affixed to the rearward end thereof, a pair of oppositely disposed resilient members comprising counteracting expansion springs having one end of each attached at opposed points in said feeler case and the opposite ends being attached at adjacent points on said stem member, said springs being adapted to stabilize said stem member in a centralized position within said case and further adapted to urge said feeler tip and stem member to a fully extended position therefrom.

3. In a feeler mechanism for looms, the combination of a feeler case, a pivot member, a stem member having a first portion extending in a direction substantially perpendicular to the axis of the bobbin from which it is adapted to derive an indication and a second portion extending from the forward end of said first portion and in a direction substantially perpendicular thereto, said pivot member being effective to limit rearward movement of said stem member and also being adapted to guide forward and rearward motion of said first portion of said stem member, said stem member including a feeler tip affixed to the rearward end thereof, a pair of oppositely disposed resilient members comprising counteracting expansion springs having one end of each attached at opposed points in said feeler case and the opposite ends being attached at adjacent points on said stem member, said stem member being provided with a plurality of spring connecting points along the length thereof for

varying the spring tension imparted to said stem and for stabilizing the same in a centralized position within said case and further adapted to urge said feeler tip and stem member to a fully extended position therefrom.

4. In a feeler mechanism for looms, a feeler case, a 10
slidable and pivotal stem member extending from said case and a feeler tip affixed to the end thereof, said stem member having a first portion extending in a direction substantially perpendicular to the axis of the bobbin from which it is adapted to derive an indication and a second portion extending from the forward end of said first portion and in a direction substantially perpendicular thereto, said feeler case including a pivot member and a guide member generally aligned and centrally disposed for guiding the forward and rearward motion of said 15 first portion of said stem member, the combination of said second portion and said pivot member being effective to limit rearward movement of said stem member, a pair of oppositely disposed coil spring members for stabilizing and

urging said stem member to a centralized and fully extended position from said feeler case, said springs having one end of each attached to adjacent points on said stem member, the latter having a plurality of such attaching points along the length of said first portion for selectively varying the spring tension imparted thereto, said spring members being disposed as to extend obliquely in the direction of the feeler tip from said first portion to opposed attachment points at the sides of said feeler case.
